UNITED STATES PATENT OFFICE.

CARL PETERS, OF ST. LOUIS, MISSOURI.

AEROPLANE.

1,421,550.

Specification of Letters Patent. Patented July 4, 1922.

Application filed June 11, 1918. Serial No. 239,382.

To all whom it may concern:

Be it known that I, CARL PETERS, a subject of Russia, residing at St. Louis, in the State of Missouri, have invented certain new and useful Improvements in Aeroplanes, of which the following is a specification.

This invention relates to improvements in aeroplanes, and the prime object thereof is the provision of means whereby an aeroplane may "hover" or remain practically motionless in the air or rise vertically at the will of the operator.

Referring to the drawings, which are more or less diagrammatic in character and wherein like numerals indicate like parts, Figure 1 is a front elevation of a biplane embracing my invention; Figure 2 a side elevation of the machine shown in Figure 1; Figures 3 to 9, inclusive, detail views, on enlarged scale, depicting the construction and arrangement of various important elements of my invention which shall hereinafter be particularly described.

The engine of the machine is indicated by numeral 1 and the same is enclosed by the housing 2. The crank shaft 3 extends beyond the radiator 4 and serves to rotate the tractor propeller 5 which is retained by nut 6 or other suitable means. Projecting through brackets 7 mounted upon the top of the engine is a rod 8 having a threaded extremity 9 (Figure 6) upon which is mounted a wheel 10, the latter having a grooved hub 11 retained between the engine housing 2 and plate 12 affixed thereto and thus serving to reciprocate said rod when turned to right or left by the operator. The forward portion of said rod is bent downwardly opposite the radiator and terminates

in a strap surrounding a grooved collar 13 which reciprocates on spline 14 affixed to shaft 3. Said collar is provided with a hub 15 which is slotted at 16-17 for the reception of arms 18-19, said arms being secured to said hub by screws 20 and their opposite extremity being fixed eccentrically to the top 21 of plugs 22-23 which are connected by bolt 21^a and tightly screwed within pipes 24-25, whereby the latter, supported by the tubular casing 26, are turned in response to the forward or rearward movement of collar 13 by rod 8 and thus alter the pitch or angle of propeller blades 5 affixed to said pipes by bolts 27-28.

The machine is supported, in landing, by wheels 29 connected by axle 30 to which is

secured a V-shaped brace 31 pivotally connected at 32 to a plate 32^a disposed over and depending from spring 33 and affixed thereto by bolts 34. Connected to the opposite ends of said axle and extending upward therefrom are curved tubes 35 which extend within sleeves 36 and are closed by screw-plugs 37, the latter serving to retain an extremity of rods 38 which project through screw-caps 39 at the upper end of said pipes and are provided with helical springs 40 disposed beneath and bearing against said caps. As shown in Figure 3, rods 38 are threaded at 38^a for engagement with the hub 41^a of helical gears 41 which mesh with worms 42 and it will be noted that upon the opposite side of gears 41 said hub is engaged by comparatively short rods 43 which are provided with threads 44 cut in a manner reverse to the threading of rods 38, whereby rotation of worms 42 by shafts 45 through the agency of bevel gears 46, 47 and 48 (Figure 8) will result in forcing rods 38 and 43 apart or drawing them together according to the direction in which the operator turns gear 47 by means of wheel 49 and the connecting shaft 50 (Figure 2).

Again referring to Figure 8, it will be seen that gears 41 and worms 42 are retained in mesh by the provision of collars 51 (one of which is shown) fixed upon shafts 45 and upstanding brackets 52 secured to an extremity of said shafts, these elements serving to support the rigidly connected links 53, 53^a and 53^b of which the latter is curved so as to fit closely against the hub 41^a of gears 41. The center portion of shafts 45 is formed of two sections 45^a-45^b which are pivotally secured at 54-54^a to the yoke connections 55 and project within a sleeve 56 which is retained against movement by engagement with threads 57 provided upon shaft section 45^b. As indicated at 58-59 sleeve 56 is provided with a narrow, oblong slot through which a pin 60 is projected which passes through shaft section 45^a, whereby the latter may be drawn outwardly from said sleeve when that portion of the shaft extending to the left of pivot 54^a (Figure 8) is raised by the forcing upward of one of rods 38 in response to the lateral movement of tubes 35 occasioned by the swinging of brace 31 upon pivot 32 when the machine tilts laterally during flight. It will, of course, be ap-

preciated that when one of rods 38 is thus forced upward the corresponding rod on the opposite side is simultaneously drawn down. Rods 43 are pivotally connected at 61 to the bell-crank levers 62 which are fulcrumed at 63 upon brackets 64 mounted upon pipes 65, said levers being connected with others of the same character, indicated at 66, by rods 67. Pipes 65 serve to enclose the shafts 66 which are driven by crank-shaft 3 through the agency of bevel-gears 68, 69 and 69^a, the driven shafts terminating in bevel-gears 70 which mesh with similar gears 71 supported upon ball-bearings 72 by arms 73 mounted upon said pipes. As may be noted by reference to Figures 3 and 7, each of the levers 66 terminates in a pointed member 74 which projects within a cone-shaped depression 75 formed in the head of shaft 76, the latter being supported by a disc 77 which is affixed to a yoke 78 depending from said member and provided with a raceway for the retention of anti-friction balls 79. Shaft 76 is projected through a sleeve 80 fastened to the hub 71^a of gear 71 by a small pin or screw 81 and the lower extremity of said shaft is connected with links 82 which engage lugs 83 extending laterally from the top of screw-plugs 84 and formed integral therewith as best shown in Figures 4 and 5. Plugs 84 are screwed tightly within tubes 85 and are connected as shown in Figures 3, 5 and 9 by bolts 86-87, one of which is provided with an enlarged, square-cut end 86^a which is engaged by socket 87^a formed as an extension of bolt 87 and secured thereto by bolt 88. Tubes 85 carrying the propellers 89 are supported by the casing 90 and the latter is affixed to pipe 91 which is secured by pin 92 to sleeve 80 and rotates in unison therewith, whereby said propellers are driven.

Referring to Figure 2 it will be noted that an additional pair of sustaining propellers 93-94 are disposed beneath the rear portion of the machine intermediate the forward sustaining propellers 89, the former having precisely the same operative elements as disclosed in Figures 3, 5 and 7 heretofore described and being driven through the agency of bevel-gears 95-95^a meshing with like gears 96-96^a affixed to shafts 97-98. Shaft 98 extends forward within the engine housing and carries a gear 99 meshing with gear 100 affixed to crank-shaft 3, while shaft 97 is rotated by the engagement of bevel-gears 95 and 101.

The rear portion of the machine is supported while at rest by a wheel 102 mounted upon the lower extremity of a rack 103 which engages a pinion 104 fixed upon a stub-shaft journaled in adjacent portions of the frame-work, said pinion having a lever 105 connected with a spring 106 and said rack having an angular bifurcated ex-

tension enclosing the upper portion of a similarly constructed rack 107 which also engages said pinion. Bell-crank levers 108-109 (corresponding in structure and function to levers 62 and 66 shown in Figure 3) are connected by rods 110-111 to rack 107 and are automatically operated so as to lessen the pitch or angle of propellers 93-94 during the forward and upward travel of the machine by the slight forward movement of said rack occasioned by the simultaneous rearward swing of the comparatively heavy rack 103, both racks again assuming the position shown in Figure 2 when the operator straightens propeller blades 5 so as to stop the traction of the machine. Operation of levers 108-109 may also be effected by rotation of wheel 112 so as to wind cord 113 upon sheave 114 affixed to shaft 115, thus rotating pinion 104 through the agency of lever 105 which results in lowering rack 103 and lifting rack 107, said racks being eventually returned to their normal position (as shown) by the pull of spring 106.

Having thus fully described the invention and the construction and operation of its several elements, what I claim as new and desire to secure by Letters-Patent is:

1. A flying machine comprising a tractor propeller, propellers disposed adjacent to the ends of its sustaining surface or surfaces and rotating in a plane substantially parallel thereto, mechanism under control of the operator for altering the pitch or angle of the blades of said propellers to lift the machine vertically, a member pivotally suspended from the machine adapted to operate said mechanism in response to lateral inclination of said surface or surfaces to correct such inclination, sustaining propellers disposed beneath the tail of the machine and rotating in a plane substantially parallel thereto, means for altering the pitch or angle of the blades of said tractor during flight to control the speed of the machine independent of the speed of the engine and automatic means for reducing the pitch or angle of the blades of said sustaining propellers during movement of the machine by said tractor.

2. A flying machine comprising a tractor propeller, propellers disposed adjacent to the ends of its sustaining surface or surfaces and rotating in a plane substantially parallel thereto, mechanism under control of the operator for altering the pitch or angle of the blades of said propellers to lift the machine vertically, a member pivotally suspended from the machine adapted to operate said mechanism, independent of the control of the operator, in response to lateral inclination of said surface or surfaces to correct such inclination, sustaining propellers disposed beneath the tail of the ma-

chine and rotating in a plane substantially parallel thereto, means for altering the pitch or angle of the blades of said tractor during flight to control the speed of the machine 5 independent of the speed of the engine, and automatic means for reducing the pitch or angle of the blades of said sustaining pro-

pellers during movement of the machine by said tractor.

CARL PETERS.
